UNITED STATES PATENT OFFICE.

JOHN M. RUSNAK, OF HARTFORD, CONNECTICUT, ASSIGNOR TO PRATT & WHITNEY COMPANY, OF NEW YORK, N. Y., A CORPORATION OF NEW JERSEY.

MULTIPLE-SPINDLE DRILLING MACHINE.

Application filed December 2, 1922. Serial No. 604,482.

This invention, as illustrated in the drawings, relates primarily to drilling machines and more especially to a multiple spindle drilling machine. Such a machine ordinarily comprises a supporting column on which a drill spindle supporting head is slidably mounted. Means is provided for rotating the drill spindle or spindles in the head and other means is provided for moving the head slowly downward on the column for feeding or rapidly in either direction for traversing. One object of the invention is to provide an improved drilling machine of the type stated adapted to function either as a semi-automatic machine wherein all the feeding and traversing movements of the head are power operated and controlled automatically or as a plain drilling machine wherein only the feeding movement is performed by power, the head being adapted to be traversed in both directions by hand.

Another object of the invention is to provide an improved drilling machine adapted to be constructed in its simpler form to provide a hand or plain drilling machine wherein only the feeding of the drill spindles is performed by power, the other operations being performed manually, and in its more complex form, by adding certain mechanism to the said simpler form, to provide a semi-automatic machine wherein the feeding of the drill spindles and the traversing thereof in both directions are automatically performed by power.

Another object of the invention is to provide, in a semi-automatic machine of the type defined, improved means for feeding and traversing the drill spindle head and improved means for controlling the same, such means including clutches for controlling the speed of the head and other clutches for controlling the direction of movement thereof and further means cooperating with the clutches for automatically shifting the same to provide the desired feeding and traversing movements.

A further object of the invention is to provide a semi-automatic drilling machine of the type stated with improved clutch means for rapidly traversing the head downwardly to the work, slowly feeding the head

downwardly during the drilling operation and rapidly traversing the head upwardly to the original position, the head being automatically stopped in a position to again repeat the cycle of operations, and a tappet wheel operatively connected with the head for automatically controlling the head moving means.

Another object of the invention is to provide, in a machine of the type stated, a disengageable driving connection between the power element and the drill spindle head and means cooperating therewith and preferably on the head for either engaging or disengaging such connection and further cooperating means for automatically disengaging such connection at the end of a predetermined feeding movement of the head.

Another object of the invention is to provide a multiple spindle drilling machine with an improved spindle grouping and driving arrangement.

A further object of the invention is to provide a drilling machine of the type stated with an improved reservoir arrangement for holding a supply of lubricant, such reservoir being formed by coring out the base or bed of the machine.

Another object of the invention is to provide an improved counterbalancing mechanism for the drill spindle head, such mechanism providing for an accurate counterbalancing of the head and safety means in connection therewith for preventing the dropping of the head should the counterbalancing mechanism fail.

With the above and other objects in view, my invention consists in the features of construction and operation set forth in the following specification and illustrated in the accompanying drawings. In such drawings annexed hereto and forming a part of this specification, I have shown my invention as embodied in a multiple spindle drilling machine but it will be understood that the invention can be otherwise embodied and that the drawings are not to be construed as defining or limiting the scope of the invention, the claims appended to this specification being relied upon for that purpose.

Referring to the figures of the drawings: Figure 1 is a front elevation of a combined

- plain and semi-automatic multiple spindle drilling machine comprising my invention. Fig. 2 is a side elevation thereof. Fig. 2^a is a fragmentary enlarged view of 5 a portion of Fig. 2. Fig. 3 is an elevation of the opposite side of the machine. Fig. 4 is an enlarged fragmentary plan view of a portion of the machine. 10 Fig. 5 is an end elevation of the feed box with the cover plate removed. Fig. 6 is an elevation of the other end of the feed box with the cover plate removed. Fig. 7 is a sectional view therethrough 15 on line 7—7 of Fig. 6. Fig. 8 is a sectional view thereof on line 8—8 of Figs. 5 and 6. Fig. 9 is a fragmentary side elevation 20 of a portion of the machine. Fig. 10 is a rear elevation thereof. Fig. 11 is a detail view taken on line 11—11 of Fig. 9. Fig. 12 is a fragmentary plan view of the drill head taken approximately on line 25 12—12 of Fig. 1. Fig. 13 is a sectional view thereof on line 13—13 of Fig. 12. Fig. 14 is a sectional view thereof on line 14—14 of Fig. 12. 30 Fig. 15 is a perspective view showing my improved drill head counterbalancing mechanism. Fig. 16 is an enlarged front elevation of the feed box partially in section. 35 Fig. 17 is a face view of the automatic clutch controlling tappet wheel with the tappets mounted thereon. Fig. 18 is a section therethrough on line 18—18 of Fig. 17. 40 Fig. 19 is a detail sectional view on line 19—19 of Fig. 17. Fig. 20 is a plan projected view of one of the levers shown in Fig. 17. 45 Figs. 21 and 22 are elevations respectively of plates mounted on the feed box and used in connection with the pointers shown in Fig. 16. Fig. 23 is an enlarged fragmentary sectional view showing in detail certain of the 50 spindle driving mechanism shown in Fig. 14. Fig. 24 is a fragmentary perspective view of cooperating driving elements shown in Fig. 23. 55 Fig. 25 shows several projected views illustrating diagrammatically the various driving elements and connections for moving the drill head on the column and for rotating the drill spindles. 60 Fig. 26 is a plan view of the improved base or bed plate of my machine. Fig. 27 is a side elevation thereof. Fig. 28 is a cross section therethrough 65 on line 28—28 of Fig. 26. Fig. 29 is a cross section on line 29—29 of Fig. 26. Fig. 30 is a fragmentary detail section taken on line 30—30 of Fig. 26. Fig. 31 is a fragmentary detail section 70 taken on line 31—31 of Fig. 26. Fig. 32 is a fragmentary side elevation of the machine showing the same constructed as a plain drilling machine. Fig. 33 shows diagrammatic views of the 75 gearing in the feed box shown in Fig. 32. Fig. 34 is a diagrammatic view of a portion of the drill head moving mechanism used in the plain drilling machine. Fig. 35 is a rear view of the column showing certain of my improved counter- 80 balancing mechanism. Fig. 36 is a cross section through the column on line 36—36 of Fig. 35. 85 My invention comprises a drilling machine construction so designed that the same, in its simpler form, is a hand or plain drilling machine and in its more complex form becomes a semi-automatic drilling machine. In shop terms and in the usual mechanical parlance, such a semi-automatic drilling machine as herein shown and described is known as an automatic multiple spindle drilling machine. However, since such machine is not in fact fully automatic, the same is herein termed "semi-automatic". The 90 original cost of a plain drilling machine is considerably less than an automatic or semi-automatic machine and such plain machine is more adapted to certain classes of work. By adding certain other mechanism to the plain drilling machine illustrated herein, the same may be converted into a semi-automatic drilling machine, which machine is also adapted to be used as a plain drilling machine when desired. By such a standardized construction, the manufacture of 95 these two types of drilling machines is greatly simplified and the adaptability of the semi-automatic machine to use as a hand machine is of considerable advantage. 100 The machine comprises in its simpler form a plain drilling machine wherein power means is provided for feeding the drill head downwardly during the drilling operation and manually operated means is provided for traversing the head in either direction on the column. Means is further provided for automatically disengaging the said power means to stop the feeding at the end of the drilling operation, the operator thereafter moving the head away from the work by the said manually operated means. By adding certain mechanism to the said 110 simpler form of the machine just described, the same may be converted into a semi-automatic drilling machine. In such machine, power means is provided for rapidly traversing the head downwardly to the work, 115 120 125

changing said rapid movement to a slow feeding movement for performing the drilling operation and thereafter rapidly returning the head to its original position. In 5 this form of the machine, the operator is only required to place the work and trip a latch which sets the machine in operation. It should furthermore be understood that, whenever desired, the mechanism added to 10 the simpler form of the machine to make the same semi-automatic may be readily disengaged whereby to render the same inoperative and adapt the semi-automatic machine to perform the functions of the said 15 plain drilling machine.

Referring more specifically to the drawings by reference characters, 1 indicates the base and 2 the column of my improved drilling machine. Mounted for vertical sliding 20 movement on the column is a drill head 3. The head is preferably mounted on the column in the novel manner illustrated in Fig. 12. A pair of vertically extending V-shaped recesses 4 are formed in the guideway 25 portion 5 of the column and are adapted to receive a pair of V-shaped projections 6 on the head. A pair of straps 7 secured to the head by bolts 8 engage rear surfaces of the guideway 5 and hold the projections 30 6 of the head firmly seated within the recesses 4 in the column. In this manner the head is firmly supported and accurately guided in its movements on the column. It should be noted that this construction also 35 eliminates the use of the usual taper adjusting gibs.

In a large machine of the type illustrated, the weight of the head 3 is considerable. It is therefore necessary to counterbalance 40 this weight and this function is preferably accomplished by the novel counterbalancing arrangement shown in Figs. 2 and 15. A main weight 9 movable vertically in the center of the column is connected to the head 3 by a pair of cables 10 passing over sheaves 11 and 12. The cables, at one end, are respectively secured to the ends of an equalizer bar 13 pivoted at its center to the weight 9 whereby each cable supports an equal portion 45 of the weight. One cable is secured rigidly to the head at 14. The other cable is connected to an element 15 slidably mounted in the head. A spring 16 between the lower end of the element 15 and a bushing 17 secured to the head normally forces the element downwardly. The tension on the cable holds the spring compressed, a washer 18 on the element limiting the upward movement of the element by contacting with the head. A link 19 operatively connects the element 15 with an arm 20 on a shaft 21 in the head and provided thereon with a toothed member 22 adjacent a vertically extending rack 23 on the column. Should the cable break or the tension thereon be re-

leased for any cause, the expansion of the spring 16 will move the member 22 about its pivot and engage the teeth thereon with the rack thereby supporting the head against downward movement. 70

The rear wall of the column is curved transversely to receive therein a second weight 24 movable vertically within a guard 26 secured to the column (Figs. 35 and 36). A centrally located cable 25 passing over 75 sheaves 27 connects the head 3 to the weight 24. The weight 24 is provided with a plurality of varied sized removable sections 24' whereby to compensate for the weight of any parts added or removed from the head. 80 An opening 26', normally closed by a removable cover plate, is formed in the guard 26 whereby the operator may have ready access to the weights 24'. In this manner the head may be accurately counterbalanced for 85 the particular drilling operation to be performed. Also the safety device in connection with one of the cables 10 positively prevents a dropping of the drill head should the counterbalancing mechanism fail to support the same. 90

Rotatably mounted within the head 3 are a plurality of drill driving spindles 28 rotated from a spline shaft 29 through mechanism hereinafter described. The head is 95 adapted to be moved vertically on the column both for feeding and traversing by mechanism also hereinafter described. I preferably rotate the drill spindles and move the head on the column from a single source 100 of power and such power may either be a motor 30, shown in Figs. 2 and 3, or a belt pulley 31 driven from a belt 32 as shown in Fig. 25. The shaft 29 and spindles 28 are rotated from a belt pulley 33 through a belt 105 34 as hereinafter described. The head 3 is moved vertically on the column by gearing and other mechanism within a feed box 35 on one side of the column, such mechanism moving the head through a spline shaft 36. 110 Means including a tappet wheel 37 on the other side of the column automatically controls the mechanism within the feed box. 115

The motor 30 is mounted on a bracket 38 and controlled by a switch controller 39. A pinion 40 on the motor shaft meshes with a gear 41 on a shaft 42 carrying the pulley 33. A pulley 43 between the gear and pulley 33 is adapted to drive a lubricating pump 44 through a belt 45. If the machine is to be 120 belt driven instead of motor driven, the belt pulley 31 is mounted on the shaft 42 in place of the gear 41, as shown in Fig. 25. The pulley 33 on the shaft 42 drives a pulley 46 through the belt 34. The mechanism for 125 driving the spindle spline shaft 29 from the pulley 46 is shown in Fig. 25. Two gears 47 and 48 secured to the pulley shaft 49 may respectively be engaged by gears 50 and 51 splined for sliding movement on a parallel 130

shaft 52, a lever 53 being provided for shifting such gears. Two pairs of gears 54, 55 and 56, 57 are secured to the shaft 52 and are respectively adapted to be engaged by pairs 5 of gears 58, 59 and 60, 61 slidably splined on a shaft 62, levers 63 and 64 being provided for shifting such gears. A bevel gear 65 journaled within a gear box 66 and within which the shaft 29 is splined for vertical 10 movement, is in engagement with a bevel gear 67 on the end of shaft 62. It will, therefore, be seen that the shaft 29 may be rotated at any one of eight speeds from the change speed gearing within the box 66. To 15 assist the operator in reaching the levers 53, 63 and 64, I mount a hand rod 68 on the column and provide steps 69 and 70 on the feed box 35.

Rotatably mounted in the lower portion 20 of the head 3 are two circularly arranged clusters of drill driving spindles 28. These spindles are rotated from the shaft 29 as follows: A gear 71 on the shaft 29 within the head meshes with a gear 72 on a parallel 25 shaft 73. This shaft 73 is located forwardly of the shaft 29 and between the said two clusters of drill driving spindles. A smaller gear 74 on the shaft 73 meshes with a gear 75 on each of two shafts 76 respectively 30 adapted to drive the said clusters of spindles. A second gear 77 on each of the shafts 76 meshes respectively with gears 78 on the spindles 28 in each cluster. It will be noted 35 that the gears 78 are in staggered relation whereby such gears may overlap without interfering with the operation of each other. The lower surface 79 of the head is provided with intersecting T-slots 80 whereby one or a plurality of drill supporting arms 81 may 40 be secured to the head. The inner end of each arm is adapted to rotatably support a drill holding spindle proper 82 and a universal driving connection 83 is adapted to operatively connect each drill spindle 82 to 45 a driving spindle 28.

My novel and improved means for quickly and securely connecting each universal driving connection 83 to a driving spindle 28 is best illustrated in Figs. 14, 23 and 24. The 50 spindle 28 of each gear 78 has bearing ends 78' integrally formed therewith. A pin or shaft 84 is pinned within the lower end of each gear 78 and the downwardly projecting end of such shaft is circumferentially 55 grooved at 84'. The uppermost element 83' of the universal driving connection 83 is adapted to fit over the grooved end of the shaft 84 and to be operatively connected to the gear 78 by oppositely disposed lugs 85 60 on the element engaging within slots 85' in the end of the gear. A pair of oppositely disposed screws 86 threaded into the element 83' may be engaged within the groove 84' to hold the element upwardly against the gear 65 with the lugs 85 engaged within the slots

85'. As will be noted, the construction provides a rigid driving connection between the gear 78 and the element 83' which connection may be readily and easily engaged or disengaged merely by rotating the screws 86. 70

The before mentioned shaft 42 extends into the column 2 and is supported in bearings 87 and 87' therein. Mechanism within the feed box 35 and operated from this shaft is adapted to slowly drive the spline shaft 75 36 in a manner to feed the head 3 downward for drilling and to rapidly drive shaft 36 for traversing the head in either direction. A bevel gear 88 and a spur gear 89 on the shaft 42 are respectively adapted to drive the 80 feeding and traversing mechanisms. It will be understood that the power traversing mechanism is used only in connection with the semi-automatic machine. The feed mechanism from the bevel gear 88 will first be 85 described.

The bevel gear 88 meshes with a bevel gear 90 on a shaft 91 extending into the feed box 35. A worm 92 on this shaft engages a worm wheel 93 on a shaft 94 extending 90 parallel with the shaft 42. A gear 95 keyed to the outer end of shaft 94 drives a gear 96 keyed to a shaft 97 through an idler gear 98 carried by an arm 99 mounted to swing about the shaft 94. Eight different sized 95 gears 96 are provided, any one of which may be keyed to the shaft 97. The gears 96 not in use may be stored in compartments 96' in the base of the machine. The idler gear 98 is always in mesh with gear 95 and the 100 arm 99 may be swung about the shaft 94 to mesh the idler with any one of the different sized gears 96, a clamping bolt 100 being provided on the feed box and extending through a slot 101 in the arm for securing 105 the arm in place. It will, therefore, be seen that the shaft 97 may be driven at any one of eight speeds from the shaft 94. A removable cover plate 102 provides easy access to these change gears. The shaft 97 is 110 adapted to drive a parallel shaft 103 through change speed gears 104 and 105 on such shafts, the gears 104 being keyed to shaft 97 and the gears 105 being loose on shaft 103. A key 106 slidable within the shaft 103 is 115 adapted to operatively connect any one of gears 105 to such shaft. The key is operated from a shaft 107 having a pinion 108 thereon meshing with a circular rack 109 on which the key is mounted. The shaft 107 is operated from a parallel shaft 110 having an outside operating handle 111 and operatively connected to the shaft 107 by intermeshing pinions 112 on such shafts. A bevel 120 gear 113 rotatable in a bearing 114 and loose on the shaft 103 is in mesh with a bevel gear 115 keyed to the spline shaft 36. A clutch 116 splined to the shaft 103 has clutch teeth for engaging clutch teeth on the bevel gear 113 to connect such gear to its shaft 103. 130

From the mechanism just described, it will be seen that the spline shaft 36 may be driven from the bevel gear 88 on the shaft 42 at any one of twenty-four speeds, each of the eight speeds obtained by change gears 96 being multiplied by the three speeds obtained by sliding the key 106. The primary function of the sliding key change gearing is to slightly vary the feeding speed obtained by the change gear 96. This feeding mechanism may also be made operative or inoperative by shifting the clutch 116 into or out of engagement with the bevel gear 113. This mechanism as thus far described is substantially the same as that used in the plain drilling machine illustrated in Figs. 32, 33 and 34.

The spline shaft 36 is adapted to be rotated rapidly from the gear 89 for traversing the drill head in either direction through the following mechanism: The gear 89 meshes with an idler gear 117 in mesh with a gear 118 loose on the shaft 94 within the feed box 35. The gear 118 meshes with a gear 119 loose on a shaft 120. A clutch 121 splined to this shaft is adapted to operatively connect the gear 119 to the shaft 120 when desired. A bevel gear 122 keyed to the end of shaft 120 meshes with two bevel gears 123 and 124 loose on a vertical shaft 125 adjacent and parallel to the spline shaft 36. A double clutch 126 splined to the shaft 125 may be shifted into clutching engagement with either of bevel gears 123 or 124. A gear 127 is mounted on a sleeve 128 keyed to the shaft 125. This gear is frictionally mounted on the sleeve between a shoulder 129 integral therewith and a plate 130 slidable thereon, a spring 131 normally operating to force the plate toward the shoulder in a manner to frictionally squeeze the gear between friction disks 129' and 130' adjacent the shoulder and plate. This gear 127 meshes with a pinion 132 keyed to the spline shaft 36.

Through the mechanism just described the spline shaft 36 may be driven at a relatively rapid speed from the gear 89 on the shaft 42. By shifting the clutch 126 to engage bevel gears 123 or 124, the shaft 36 may be driven in one direction or the other. This mechanism may also be made operative or inoperative by shifting the clutch 121 into or out of engagement with the gear 119. The frictionally mounted gear 127 is adapted to slip and thereby prevent shock to the machine when the rapid traverse mechanism is thrown into operation.

The feed clutch 116 may be shifted by a yoke 133 and the traversing clutch 121 may be shifted by a yoke 134. In order to prevent the simultaneous engagement of these clutches and for the purpose of engaging one clutch when disengaging the other, these clutches are connected together by a rod 135

adjustably jointed at 136. The shifting of the clutches in both directions is limited by set screws 137 and 138 screw threaded into arms 137^a and 138^a on the yoke 133 and adapted to engage the lugs 137^b and 138^b on the box 35. The clutch yoke 134 is mounted on a shaft 139 which extends through the box 35 and column 2, as shown in Figs. 1 and 4. One end of the shaft projects outwardly of the feed box and is squared at 139' to receive a wrench for shifting the clutches manually. On this end of the shaft is mounted an arm 140 having a V-shaped plug 140' seated in its free end. A V-shaped plunger 141 above the shaft is pressed downwardly by a spring 142 into engagement with the V-shaped plug 140' in the end of the arm whereby to assist the shaft 139 to fully engage one or the other of clutches 116 and 121. The spring and plunger are held in place by a threaded plug 143.

By reference to Fig. 7, it will be seen that the clutch shoes 133' and 134' engaging respectively within the clutch grooves 116' and 121' are slightly narrower than the said grooves whereby the shoes are permitted a limited free movement axially of the clutches. The mechanism is so adjusted that the V-shaped plug 140' is moved past the center of the spring pressed plunger 141 before the clutch being disengaged is fully disengaged whereby such plunger operates to quickly snap the clutch out of engagement and thus avoid driving the mechanism with only the ends of the clutch teeth engaged. The loose mounting of the clutch shoes as above described permits this quick disengaging movement of the clutches independently of the clutch shifting mechanism. This function eliminates the crumpling away of the ends of the clutch teeth as will be readily understood. A pointer 144 adjacent the squared shaft end 139' is adapted to indicate on a plate 145 whether the fast traversing clutch 121 or the feed clutch 116 is in the engaged position.

The clutch 126 is shifted by a yoke 146 mounted on a shaft 147. One end of the shaft 147 projects outwardly of the feed box 35 and is squared at 147' to receive a wrench for shifting the clutch 126 manually. On this end of the shaft is mounted an arm 148 having a V-shaped plug 148' seated in its free end. A V-shaped plunger 149 above the shaft is pressed downwardly by a spring 150 into engagement with the V-shaped plug 148' in the end of the arm whereby, to assist the shaft 147 to fully engage the clutch 126 with one or the other of the bevel gears 123 and 124. The spring and plunger are held in place by a threaded plug 151. By reference to Fig. 7, it will be seen that the clutch shoes 146' engaging within the clutch groove 126' are slightly narrower than the said groove 130.

whereby the shoes are permitted a limited free movement axially of the clutch. The mechanism is so adjusted that the V-shaped plug 148' is moved past the center of the 5 spring pressed plunger 149 before the clutch is fully disengaged from one or the other of the bevel gears 123 and 124 whereby such plunger operates to quickly snap the clutch out of engagement and thus avoid driving the 10 mechanism with only the ends of the clutch teeth engaged. The loose mounting of the clutch shoes as above defined permits this quick disengaging movement of the clutch independently of the clutch shifting mechanism as has been heretofore described in 15 connection with clutches 116 and 121. A pointer 152 adjacent the squared shaft end 147' is adapted to indicate on a plate 153 whether the clutch 126 is engaged with the 20 head lowering bevel gear 123 or the head elevating bevel gear 124.

The shaft 147 is operatively connected to a shaft 154 by means of arms 155 and 156 secured to such shafts and connected by a 25 link 157. The shaft 154 extends through the box 35 and the column 2 as shown in Figs. 1 and 4. The shifting of the clutch 126 in both directions is limited by set screws 158 and 159 screw threaded into 30 branches 158^a and 159^b of an arm pinned to the shaft 154, the set screws being adapted to engage lugs 158^b and 159^b on the box 35. The mechanism for automatically shifting the clutches through the shafts 139 and 154 35 will be hereinafter described.

Integral with the arm 148 within a box 160 is a horizontally extending arm 161 (Fig. 16) having a latch plug 162 seated in the free end thereof. A bell crank lever pivoted at 163 has a latch plug 164 seated in the 40 end of a vertical arm thereof, such latch being adapted to cooperate with the latch 162. A spring pressed plunger 165 normally keeps the latch 164 engaged with the latch 162. A rod 166 connects a horizontal arm 167 of this lever with a horizontal arm of a bell crank 168. A horizontal rod 169 connects a vertical arm of the bell crank 168 with an arm of a foot pedal 170 at the 45 front of the machine. When the shaft 147 is rotated to shift the clutch 126 from engagement with the bevel gear 124 toward bevel gear 123, the latch 164 engages latch 162 and holds the clutch and its connected 50 parts in the position shown in Figs. 7 and 16. It will be noted that the clutch is thus held in the neutral position and that the V-shaped plug 148' is beyond the center of the spring pressed plunger 149. When the 55 operator steps on the pedal 170, the latch 164 will permit the plunger 149 to engage the clutch 126 with the bevel gear 123 to cause a rapid downward traversing of the head 3 as hereinafter described.

60 The head 3 is moved vertically on the

column 2 from the spline shaft 36 through the following mechanism: The rack 23 secured to the column is engaged by a pinion 171 on a shaft 172 mounted in the head 3. The following mechanism housed by a casting 173 provides a driving connection between the spline shaft 36 and the rack pinion shaft 172. A housing 174 is mounted for swinging movement on the shaft 36 within the casing 173. This housing carries a pinion 175 splined to the shaft 36 and a second intermeshing pinion 176 on a shaft 177. Integrally or otherwise secured to the pinion 176 is a worm 178 adapted to be engaged with a worm wheel 179 on a shaft 180. A 75 pinion 181 on the shaft 180 is in mesh with a gear 182 on the rack pinion shaft 172.

A spring pressed plunger 183 mounted in the casing 173 (Fig. 12) and engaging against a projecting portion 184 of the housing 174 normally swings the housing about the shaft 36 in a direction to disengage the worm 178 from the worm wheel 179. An arm 185 secured to a horizontal shaft 186 is provided with a set screw 187 in its free end adapted to engage a rearwardly extending projection 188 on the housing. A horizontal rod 189 slidably mounted on the casing 173 (Fig. 2^a) has the rear end thereof connected to the free end 190 of a second 90 arm 191 secured to the end of the shaft 186. A lever pivoted at 192 has one arm 193 thereof adapted to engage a collar 194 on the rod and a second arm 195 operatively connected by a rod 196 to a handle 197 pivoted on the head 3. Movement of the handle 197 inwardly moves the rod 189 in a direction to engage the worm 178 with the worm wheel 179. A latch rod 198 normally forced into engagement with the rod 189 by 95 a spring 199 is adapted to engage a notch 200 in the rod to hold the worm engaged with the worm wheel. The said lever pivoted at 192 has a third arm 201 extending to such a position above a collar 202 on the rod 198 that outward movement of the handle 197 will withdraw the rod 198 and permit the spring pressed plunger 183 to disengage the worm from the worm wheel and thus stop the feeding or transversing 100 movement of the head. A stop collar 189' on the rod 189 limits the inward movement of the rod.

When using the machine as a hand or plain drilling machine, as hereinafter more 105 fully described, it is desirable that means be provided for automatically stopping the downward movement of the head at the end of the desired drilling operation. Such mechanism is herein provided as follows: 110 Beneath the horizontal shaft 186 is a shaft 203 on one end of which is an arm 204 operatively connected to the latch rod 198. A second arm 205 on the shaft 203 has a bifurcated end extending about the hand rod 68. 115

120 130

A stop collar 206 on the rod 68 is adapted to be engaged by the arm 205 upon the downward movement of the head whereby the latch rod 198 is withdrawn and the 5 worm 178 automatically disengaged. The stop collar may be secured in any desired position on the rod 68 by means of a hand screw 207.

The head 3 may be moved manually on 10 the column by means of a shaft 208 having a hand wheel 209 thereon located most conveniently to the operator centrally and forwardly of the head 3. On the inner end of this shaft is a bevel gear 210 meshing with 15 a bevel gear 211 on a shaft 212. A spur gear 213 on shaft 212 meshes with a gear 214 on the rack pinion shaft 172. The hand wheel is mounted loosely on the shaft 208 whereby the same is not rotated during the automatic 20 operation of the machine. The hub of the hand wheel is provided with clutch teeth adapted to engage cooperating teeth on an element 215 keyed to the shaft. A spring 216 normally holds the clutch teeth 25 disengaged, a knob 217 being threaded to the outer end of the shaft for holding the teeth engaged against the action of the spring.

As heretofore stated, in the automatic drilling machine, the feeding and traversing clutches 116 and 121 respectively and the double reversing clutch or clutches 126 are controlled automatically. As illustrated in the drawings, such control is by the tappet wheel 37 mounted on a shaft 218. This 30 wheel is located in a box or casing 219 on the opposite side of the column 2 from the feed box 35 and tappets on the wheel cooperate with the clutch shafts 139 and 154 to control the clutches as hereinafter described. The wheel is rotated from the rack pinion shaft 172 through the following 35 mechanism: An extension 220 (Fig. 12) is pinned to the end of the rack pinion shaft 172. A bevel gear 221 loosely mounted on this extension is provided with clutch teeth adapted to be engaged by clutch teeth on an element 222 splined to the outer end of the extension. The element 222 is slidably supported in an opening in a bracket box 223 secured to the head 3 and is provided with an operating knob 224. A spring 225 surrounding the extension and bearing against a nut 226 thereon normally holds the clutch element engaged with the gear, a 40 detent 227 spring pressed by a plunger 228 may engage a shoulder 229 on the element to hold the same in a disengaged position. The detent is mounted on a shaft 230 which is provided with a handle 231 for rotating the 45 shaft to disengage the detent. A horizontal shaft 232 is provided with a bevel gear 233 on one end in mesh with the bevel gear 221, a bevel gear 234 on the other end thereof meshing with a bevel gear 235 journaled for rotation in an extension 223' of the

bracket 223 and splined to a vertical shaft 236. The lower end of this shaft 236 extends into the tappet wheel casing 219 and has a bevel gear 237 thereon meshing with a large bevel gear 238 on the tappet wheel 70 shaft 218. The tappet wheel will be rotated from the rack pinion shaft in the direction of the arrow *a* (Fig. 17) when the head 3 is moved downwardly and in the direction of the arrow *b* when the head 3 is moved 75 upwardly.

The clutch operating shafts 139 and 154 extend into the casing 219 to a position adjacent the tappet wheel 37. The shaft 154 has an arm 239 thereon rearwardly of the 80 tappet wheel and provided with a pin 240 in its free end extending forwardly toward the wheel. The shaft 139 is operatively connected to a short shaft 241 opposite the shaft 154 in the casing 219 by means of 85 arms 242 and 243 secured to such shafts and connected by a link 244. The shaft 241 has an arm 245 thereon forwardly of the tappet wheel and provided with a pin 246 in its free end extending rearwardly toward 90 the wheel. The tappet wheel has three tappets 247, 248 and 249 adjustably mounted thereon for cooperating with the pins 240 and 246.

The tappet 247 has a forward cam surface 95 247^a for engaging the pin 246 to rotate the shaft 139 in a direction to disengage fast clutch 121 and engage slow clutch 116 and a rear cam surface 247^b for engaging the pin 240 to rotate the shaft 154 in a direction to shift clutch 126 from engagement with the head lowering bevel gear 123 to engagement with the head elevating bevel gear 124 (the tappet wheel rotating in the direction of arrow *a*, head moving downward). The tappet 248 has a forward cam surface 248^a for engaging the pin 246 to rotate the shaft 139 in the opposite direction (tappet wheel rotating in direction of arrow *a*). The tappet 249 has a rear cam 100 surface 249^b for engaging the pin 240 to rotate the shaft 154 in the opposite direction (tappet wheel rotating in direction of arrow *b*, head moving upward). The tappet 247 is provided with a bevel surface *v* 105 110 for permitting the passage of the spring pressed pin 246 upon the reverse rotation (arrow *b*) of the tappet wheel. The consecutive operation of these tappets on the clutches to automatically control the operations of the machine is hereinafter specifically described.

As heretofore stated and as hereinafter specifically described in reference to the drawings, my improved drilling machine 125 construction, in its simpler form, provides a hand or plain drilling machine. A semi-automatic drilling machine such as just described may be constructed in the same manner and from the same machine by adding 130

certain cooperating elements thereto whereby the same is rendered capable of performing drilling operations automatically. The machine illustrated in the drawings is such 5 a semi-automatic drilling machine and the operation thereof will now be described.

Operation semi-automatic machine.

The following operations and adjustments 10 are necessary before performing automatic drilling operations on the machine shown in the drawings. The head 3 is illustrated as provided with twenty-four drill driving spindles 28 and an equal number of drill 15 spindles 82 mounted on supporting arms 81 may be driven therefrom. The required number of arms 81 are first mounted on the head with the spindles 82 in the proper position for performing the desired drilling operation. The worm 178 is engaged with the worm wheel 179 and is never disengaged therefrom during the operation of the automatic drilling machine, except in an emergency. The automatic feed stop is used only 20 in connection with the plain drilling machine and therefore the stop collar 206 is either removed or placed in an inoperative position on the rod 68. The clutch at 215 is left in an open position wherein the hand wheel 209 is 25 not rotated with its shaft 208. The element 222 (Fig. 12) is engaged with the bevel gear 221 whereby to rotate the tappet wheel 37 from the rack and pinion shaft 172. The proper gear 96 for giving the desired feeding speed is selected and secured in its driving position on the shaft 97. The feeding speed obtained from this gear may be further varied merely by shifting the key 106. This arrangement is of particular advantage 30 since it frequently happens that a slightly greater or less feeding speed results in a great improvement in the operation and efficiency of the machine as well as in the character of the work performed. The levers 53, 40 63 and 64 are also shifted to the proper positions to rotate the drill spindles at the required speed. Assuming that the head 3 is in its up position removed from the work, the clutches are set as follows: The shaft 139 45 is rotated manually to the left (Fig. 7) to engage the traversing clutch 121 and the clutch shaft 147 is rotated manually to the left (Fig. 7) to place the parts in the position shown in Figs. 7 and 16. The tappets 247, 55 248 and 249 are also adjusted on the tappet wheel 37 to the proper positions for giving the desired movements to the head as herein-after described.

Assuming that the several parts of the machine have been set and adjusted as above outlined, that power is being applied to the shaft 42 to rotate the drill spindles and to drive the mechanism within the feed box 35 and that a work piece has been fixed in the drilling position beneath the head 3, the op-

erator depresses the foot pedal 170 to start the operation of the machine. The latch 162 being released from the holding latch 164, the spring pressed plunger 149 rides downwardly against the V-shaped plug 148' and 70 rotates the shaft 147 in a manner to engage the clutch 126 with the head lowering bevel gear 123. The head 3 is thus traversed rapidly downward, the tappet wheel 37 being rotated in the direction of the arrow *a* (Fig. 75 17). This movement of the head continues until the drills approach the work piece and the driving mechanism is interrupted by the tappet 247.

Tappet operation.

The forward cam surface 247^a of the tappet 247 engages the pin 246 and through the shafts 241 and 139 disengages the traversing clutch 121 and engages the feed clutch 116, 85 the spring pressed plunger 141 fully completing this clutch shifting operation. The rear cam surface 247^b of this tappet engages the pin 240 and through the shafts 154 and 147 shifts the clutch 126 from engagement 90 with the head lowering gear 123 to engagement with the head elevating gear 124. The cam surface 247^a acts slightly in advance of the surface 247^b in order to assure the disengagement of the traversing clutch 121 before 95 engaging the clutch 126 with the oppositely rotating bevel gear 124. The head is now fed slowly downward through the feed mechanism including the clutch 116. At the completion of the drilling operation, the tappet 248 (having been properly adjusted on the tappet wheel) engages the pin 246, and the cam surface 248^a through such pin and shaft 139 disengages the feed clutch 116 and 100 engages the traversing clutch 121. Since the clutch 126 is in engagement with the head elevating bevel gear 124, the head will be rapidly traversed upwardly, the tappet wheel reversing to rotate in the direction shown by arrow *b*. This movement of the head continues until interrupted by the tappet 249. The cam surface 249^b of such tappet engages the pin 240 and through the shafts 154 and 147 shifts the clutch 126 from 105 engagement with bevel gear 124 upward toward bevel gear 123. The latch 164, however, prevents the engagement of clutch 126 with the bevel gear 123 and holds the parts in the relative positions shown in Figs. 7 and 16. The head now remains at rest in its original starting position while the operator removes the drilled work piece and places another piece in position for the next drilling operation. Upon again depressing the 110 pedal 170, the spring pressed plunger 149 again automatically engages the clutch 126 with the bevel gear 123 whereupon the head starts rapidly downward and the cycle of operations above enumerated are repeated. 115 If for any reason the operator desires to 120

stop the movement of the head 2, such function may be accomplished at any time merely by pulling the hand lever 197 outwardly whereupon the spring pressed plunger 183 automatically disengages the worm 178 from the worm wheel 179. It should be noted that this hand lever 197 is located most conveniently for the operator on the front portion of the head 3.

10 *Operation—Plain drilling machine.*

It may frequently be desired to perform certain drilling operations without making the adjustments necessary to operate the machine automatically. In quantity production where many identical work pieces are to be drilled all in the same manner, the automatic machine is particularly advantageous and efficient. However, where only a few pieces are to be drilled in the same manner, such operations can frequently be performed more readily on a plain drilling machine. My invention, in its simpler form, contemplates such a plain drilling machine and the automatic machine illustrated may be used as a plain drilling machine when desired by making the following adjustments.

The screw knob 217 should be tightened to engage the hand wheel 209 with its shaft 208. The stop collar 206 should be secured to the hand rod 38 in a position to stop the feeding movement of the head at the completion of the drilling operation. The clutch 35 at 222 is disengaged whereby the tappet wheel 37 is rendered inoperative. The clutch 126 is placed in the neutral position as shown in Fig. 7 and the feed clutch 116 is engaged, the traversing clutch 121 being held disengaged through the rod 135. The gearing is adjusted to give the proper rotation and feeding speeds to the drill spindles, which spindles are also set and adjusted as above described in connection with the automatic operation of the machine. The worm 178 is left in a disengaged position until the feeding of the head is to be started. With the automatic mechanism thus disengaged, the machine becomes substantially a plain drilling machine and the operation thereof is as follows.

Assuming that the several parts of the machine have been set and adjusted as above outlined, that power is being applied to the shaft 42 to rotate the drill spindles and to drive the feed gearing within the feed box 35 and that a work piece has been fixed in the drilling position beneath the head 3, the operator rotates the hand wheel 209 in a direction to move the head downwardly until the drills approach or engage the work piece. The operator then pushes the hand lever 197 inwardly to engage the worm 178 with the worm wheel 179 whereupon the head is fed downwardly at drilling speed. This opera-

tion continues until arm 205 engages the stop collar 206 whereupon the shaft 203 is rotated and the latch rod 198 withdrawn. The spring pressed plunger 183 immediately operates to disengage the worm and thereby stop the feeding movement of the head. The operator now rotates the hand wheel 209 in the opposite direction to raise the head away from the work piece. The finished work piece is now removed and another piece placed in position for the next drilling operation, the operations just enumerated then being repeated to drill such work piece.

Fig. 32 is a fragmentary view illustrating my improved machine constructed as a plain drilling machine. In such machine, the base 1, column 2, spline shaft 36 and other main parts of the machine are the same as heretofore described in connection with the semi-automatic drilling machine, a plain feed box 35^a however being substituted for the automatic feed box 35. The feed gearing within this feed box, illustrated diagrammatically in Fig. 33, is the same feed gearing heretofore described in connection with the semi-automatic machine, the rapid power traversing mechanism and the automatic features however being omitted. The reference characters indicating these identical parts in Figs. 32, 33 and 34 are primed reference characters corresponding to those used in Fig. 25.

The clutch 116^a may be shifted by applying a crank or wrench to the squared end 116^b of a shaft 116^c operatively connected to the clutch. This gearing provides a power feed for the head as heretofore described, the head being traversed manually in either direction by the hand wheel 209. It should furthermore be noted (Fig. 34) that, since this machine is not automatic in operation, the rack pinion shaft 172 is not provided with the tappet wheel operating bevel gear 221 shown in Fig. 25. It is believed that the construction and operation of this machine will be understood from the description heretofore given and for this reason, further description thereof appears to be unnecessary.

In Figs. 26 to 31, inclusive, I have illustrated in detail the novel base or bed plate 1 for supporting either type of machine above described. This base is of a flat plate-like construction having a column supporting part 250 and a work supporting part 251. The column supporting part 250 has an upper column supporting surface or portion 252 and a lower floor engaging surface or portion 253. The space between these portions is cored out at 254 to provide an oil reservoir for the machine. The center of the portion 252 is provided with a large cored opening 255 normally covered by the column which seats on the surface 252 around such opening, bolts 256 threading into the portion 252 being adapted to

secure the column to the base. Bracing ribs 257 are formed integral with the parts 252 and 253 within the reservoir whereby to rigidly support the weight of the column.

5 The pump 44, heretofore described, is mounted on the base at 258 and is adapted to draw oil from the reservoir through an opening 259 therein and to force such oil upwardly to the machine as desired. The opposite sides of the column supporting part 250 of the base are provided with drains or troughs 260 each leading into a screened opening 261 into the reservoir. A drain 262 about the end of part 250 and a drain 263

10 extending around the work supporting part 251 lead into the troughs 260 whereby any oil draining from the machine onto the base 1 is carried into the reservoir. The reservoir may be drained and cleaned when desired by removing a cover plate 264 normally closing a drain 265 opening into the bottom of the reservoir.

What I claim is:

1. A combined plain and automatic drilling machine comprising the combination of a column, a drill head, slideable thereon, a plurality of spindles mounted in the head, means for rotating the spindles, a pinion on the head engaging a rack on the column, mechanism for slowly rotating the pinion to feed the head downwardly for drilling, mechanism for rapidly rotating the pinion to traverse the head in either direction, means for automatically controlling the feeding and traversing mechanism, means for disengaging the traversing mechanism and the automatic controlling means in a manner to leave the feeding means operative independently thereof, means other than the said automatic controlling means for controlling the feeding movement of the feeding mechanism, and a hand wheel operatively connected to the pinion for traversing the head manually.
- 45 2. A combined plain and automatic drilling machine comprising the combination of a column, a drill head slideable thereon, a plurality of spindles mounted in the head, means for rotating the spindles, mechanism for slowly feeding the head downwardly for drilling, mechanism for rapidly traversing the head in either direction, means for automatically controlling the feeding and traversing mechanism, means for disengaging the traversing mechanism and the automatic controlling means in a manner to leave the feeding means operative independently thereof, a disengageable driving connection between the feeding mechanism and the head, and adjustable means for automatically disengaging such connection at the end of the drilling operation.
- 50 3. A combined plain and automatic drilling machine comprising the combination of a column, a drill head slideable thereon, a plurality of spindles mounted in the head, means for rotating the spindles, mechanism for slowly feeding the head downwardly for drilling, mechanism for rapidly traversing the head in either direction, means for automatically controlling the feeding and traversing mechanism, means for disengaging the traversing mechanism and the automatic controlling means in a manner to leave the feeding means operative independently thereof, a disengageable driving connection between the spline shaft and the head, and means for readily engaging and disengaging such connection.
- 55 4. A combined plain and automatic drilling machine comprising the combination of a column, a drill head slideable thereon, a plurality of spindles mounted in the head, means for rotating the spindles, mechanism for slowly feeding the head downwardly for drilling, mechanism for rapidly traversing the head in either direction, means for automatically controlling the feeding and traversing mechanism, means for disengaging the traversing mechanism and the automatic controlling means in a manner to leave the feeding means operative independently thereof, a disengageable driving connection between the spline shaft and the head, and means for readily engaging and disengaging such connection.
- 60 5. A combination plain and automatic drilling machine comprising the combination of a column, a drill head slideable thereon, a plurality of spindles mounted in the head, a vertically extending spline shaft, mechanism for slowly rotating the shaft for feeding the head downwardly for drilling, mechanism for rapidly rotating the shaft for traversing the head in either direction, means for automatically controlling the feeding and traversing mechanism, means for disengaging the traversing mechanism and the automatic controlling means in a manner to leave the feeding means operative independently thereof, a disengageable driving connection between the spline shaft and the head, and means for readily engaging and disengaging such connection.
- 65 6. In a drilling machine, the combination of a base, a column thereon, a drill head slideable on the column, a plurality of spindles mounted in the head, means for rotating the spindles, and two optionally usable power operated mechanisms for moving the head on the column, one mechanism comprising a system of gearing and clutches with means controlling the same for automatically traversing the head downwardly to the work, slowly feeding the head downward for drilling and traversing the head upwardly to its original position, and the other mechanism comprising a system of

means for rotating the spindles, mechanism including a feed clutch and a reversing clutch for slowly feeding the head downwardly for drilling, mechanism including a traversing clutch and the said reversing clutch for rapidly traversing the head in either direction, means operated in timed relation with the movement of the head for shifting the clutches to automatically control the feeding and traversing mechanism, and means for disengaging the traversing mechanism and the automatic controlling means in a manner to leave the feeding means operative independently thereof.

4. A combined plain and automatic drilling machine comprising the combination of a column, a drill head slideable thereon, a plurality of spindles mounted in the head, means for rotating the spindles, mechanism for slowly feeding the head downwardly for drilling, mechanism for rapidly traversing the head in either direction, means for automatically controlling the feeding and traversing mechanism, means for disengaging the traversing mechanism and the automatic controlling means in a manner to leave the feeding means operative independently thereof, a disengageable driving connection between the feeding mechanism and the head, and adjustable means for automatically disengaging such connection at the end of the drilling operation.

5. A combination plain and automatic drilling machine comprising the combination of a column, a drill head slideable thereon, a plurality of spindles mounted in the head, means for rotating the spindles, a vertically extending spline shaft, mechanism for slowly rotating the shaft for feeding the head downwardly for drilling, mechanism for rapidly rotating the shaft for traversing the head in either direction, means for automatically controlling the feeding and traversing mechanism, means for disengaging the traversing mechanism and the automatic controlling means in a manner to leave the feeding means operative independently thereof, a disengageable driving connection between the spline shaft and the head, and means for readily engaging and disengaging such connection.

6. In a drilling machine, the combination of a base, a column thereon, a drill head slideable on the column, a plurality of spindles mounted in the head, means for rotating the spindles, and two optionally usable power operated mechanisms for moving the head on the column, one mechanism comprising a system of gearing and clutches with means controlling the same for automatically traversing the head downwardly to the work, slowly feeding the head downward for drilling and traversing the head upwardly to its original position, and the other mechanism comprising a system of

- gearing for feeding the head downwardly for drilling and hand operated means for traversing the head in either direction.
7. In a drilling machine, the combination 5 of a base, a column thereon, a drill head slideable on the column, a plurality of spindles mounted in the head, means for rotating the spindles, and two optionally usable power operated mechanisms for moving the head 10 on the column, one mechanism comprising a system of gearing and clutches with means controlling the same for automatically traversing the head downwardly to the work, slowly feeding the head downward for drilling and traversing the head upwardly to its original position, and the other mechanism comprising a system of gearing for feeding the head downwardly for drilling, means automatically operative to stop the feed at 15 the end of the drilling operation and hand operated means for traversing the head in either direction.
8. In a drilling machine, the combination 20 of a base, a column thereon, a drill head slideable on the column, a plurality of spindles mounted in the head, means for rotating the spindles, and two optionally usable power operated mechanisms for moving the head on the column, one mechanism comprising a system of gearing and clutches and a wheel rotatable in opposite directions synchronously with the movement of the head and having adjustable tappets for controlling the clutches to automatically 25 traverse the head downwardly to the work, slowly feed the head downwardly for drilling and traverse the head upwardly to its original position, and the other mechanism comprising a system of gearing 30 for feeding the head downwardly for drilling and hand operated means for traversing the head in either direction.
9. In a drilling machine, the combination 35 of a base, a column thereon, a drill head slideable on the column, a plurality of spindles mounted in the head, means for rotating the spindles, and two optionally usable power operated mechanisms for moving the head on the column, one mechanism comprising a feed box adapted to be mounted on the machine and having a system of gearing and clutches and means controlling the same for automatically traversing the head downwardly to the work, slowly feeding the head downwardly for drilling and traversing the head upwardly to its original position, and the other mechanism comprising a feed box adapted to be mounted on the machine and having a system of gearing for feeding the 40 head downwardly for drilling and hand operated means for traversing the head in either direction, the last said system of gearing being substantially the same as the feeding portion of the first said system of gearing.
10. In a machine of the class described, the combination of a column, a head movable vertically thereon, tool supporting means on the head, means for driving the tools, means including a vertically extending spline shaft on one side of the column for feeding and traversing the head on the column, and means including a vertically extending spline shaft on the other side of the column operated by and synchronously in opposite directions with the movement of the head for automatically controlling the operation of the means for feeding and traversing the head.
11. In a machine of the class described, 50 the combination of a column, a head movable vertically thereon, tool supporting means on the head, means for driving the tools, means including a vertically extending spline shaft on one side of the column for feeding and traversing the head on the column, and means including a vertically extending spline shaft on the other side of the column rotated by movement of said head and operatively connected to the head moving means for automatically controlling the means for feeding and traversing the head.
12. In a drilling machine, the combination 55 of a column, a drill head movable vertically thereon, a plurality of spindles mounted in the head, means for rotating the spindles, means including a vertically extending spline shaft on one side of the column for feeding and traversing the head on the column, a gear box from which the spline shaft is driven, mechanism within the box for controlling the rotation of the spline shaft, a spline shaft on the other side of the column driven by the head and in opposite directions synchronously with the movement of the head, and means driven from the last said spline shaft for automatically controlling the movements of said head.
13. In a drilling machine, the combination 60 of a column, a drill head movable vertically thereon, a plurality of spindles mounted in the head, means for rotating the spindles, means including a vertically extending spline shaft on one side of the column for feeding and traversing the head on the column, a gear box from which the spline shaft is driven, mechanism including clutches within the box for controlling the rotation of the spline shaft, a spline shaft on the other side of the column driven by the head and in opposite directions synchronously with the movement of the head, a tappet wheel rotated therefrom, and means operated by the tappet wheel for automatically shifting the clutches for controlling the movement of the head.
14. In a drilling machine, the combination 65 of a column, a drill head movable ver-

tically thereon, a plurality of spindles mounted in the head, means for rotating the spindles, power means for feeding and traversing the head on the column, a gear box 5 on one side of the column, mechanism within the box for controlling the feeding and traversing movements of the head, and means on the other side of the column for automatically controlling the said mechanism.

15. In a drilling machine, the combination of a column, a drill head movable vertically thereon, a plurality of spindles mounted in the head, means for rotating the spindles, power means for feeding and traversing the head on the column, a gear box 15 on one side of the column, mechanism in the box including a plurality of clutches for controlling the feeding and traversing movements of the head, means on the other side of the column, operative synchronously with the movement of the head, and means forming a connection between the clutches and the third named means for automatically controlling the said mechanism.

16. In a drilling machine, the combination of a column, a drill head movable vertically thereon, a plurality of spindles mounted in the head, means for rotating the spindles, power means for feeding and traversing the head on the column, a gear box 30 on one side of the column, mechanism in the box including clutches for controlling the speed of the head and clutches for controlling the direction of movement thereof, means on the other side of the column operatively connected with the head for movement synchronously therewith, and means extending through the column and forming 35 a connection between the clutches and the third named means for automatically controlling the said mechanism.

17. In a drilling machine, the combination of a column, a drill head movable vertically thereon, a plurality of spindles mounted in the head, means for rotating the spindles, power means for feeding and traversing the head on the column, a gear box 45 on one side of the column, mechanism in the box including a plurality of clutches for controlling the feeding and traversing movements of the head, a tappet wheel on the other side of the column rotated by said head and synchronously with the movement 50 of the head, means extending through the column operatively connected to the clutches, and a plurality of tappets on the wheel adapted to cooperate with the last named means for automatically controlling the said mechanism for feeding and traversing said head.

18. In a drilling machine, the combination of a column, a drill head movable vertically thereon, power means for feeding and traversing the head on the column, means

including two oppositely rotating gears and a double clutch therebetween for controlling the direction of traverse of the head, two interconnected clutches between the power means and head, one of such clutches controlling the feed of the head and the other controlling the drive to the said two gears, and means movable synchronously with the head and operating on the clutches for automatically and consecutively giving the head 70 a rapid downward movement, a slow feeding movement in the same direction and a rapid upward movement to its original position.

19. In a machine of the class described, 80 the combination of a support, a member slidably mounted thereon, power means for sliding the member including clutches for controlling the speed and direction of movement thereof, means movable synchronously 85 with the member for controlling the clutches, such means operating to change the fast forward movement of the member to slow, to reverse the slow forward movement to fast backward movement and to again shift the 90 clutches in a direction to stop the backward movement and to cause a fast forward movement, a latch automatically operative to prevent the engagement of the fast forward clutch, and means for automatically engaging 95 such clutch when the latch is released.

20. In a machine of the class described, the combination of a support, a member slidably mounted thereon, power means for sliding the member including clutch elements controlling the speed of the member and clutch elements controlling the direction of movement thereof, means movable synchronously 100 with the member for controlling the clutch elements, such means being operative on the said speed clutch elements to change the fast forward movement to slow, on the speed and direction clutch elements to reverse the slow forward movement to fast backward 105 movement, and again on the direction clutch elements to shift the same in a direction to stop the backward movement and to cause a fast forward movement, a latch automatically operative to prevent the engagement of the fast forward clutch element, and means for automatically engaging such clutch element when the latch is released.

21. In a drilling machine, the combination of a column, a drill head movable vertically thereon, a plurality of spindles mounted in the head, means for rotating the spindles, power means for moving the head on the column including clutches for controlling the speed and direction of movement thereof, an element operatively connected to the head for movement synchronously therewith, a plurality of tappets adjustable on the element, the tappets being operative on the clutches to change the fast downward movement of the head to slow, to 110

reverse the slow downward movement to fast upward movement and to again shift the clutches in a direction to stop the upward movement and to cause a fast downward movement, a latch automatically operative to prevent the engagement of the fast downward clutch, means for automatically engaging such clutch when the latch is released, and means for releasing the latch.

22. In a drilling machine, the combination of a column, a drill head movable vertically thereon, power means including a vertically extending spline shaft rotatably supported on the column adjacent the head for feeding the head downward, a disengageable driving connection between the spline shaft and the head and including a gear slidably mounted on the spline shaft, means pivotally movable about the spline shaft as an axis for engaging and disengaging the driving connection, a latch for holding the connection so engaged, an ad-

justable stop, and means cooperating with the latch and adapted to engage the stop to withdraw the latch to automatically stop the feeding movement of the head.

23. In a drilling machine, the combination of a column, a drill head movable vertically thereon, power means including a vertically extending spline shaft rotatably supported on the column adjacent the head for feeding the head downward, a disengageable driving connection between the spline shaft and the head and including a gear slidably mounted on the spline shaft, means for engaging the driving connection, a latch for holding the connection so engaged, an adjustable stop on the column, and means on the head cooperating with the latch and adapted to engage the stop to withdraw the latch to automatically stop the head at the end of the desired feeding movement.

I testimony whereof, I hereto affix my signature.

JOHN M. RUSNAK.
